CARBURETER FOR HYDROCARBON-MOTORS.

1,145,854.

Specification of Letters Patent. Patented July 6, 1915.

Application filed November 24, 1902. Serial No. 132,519.

To all whom it may concern:

Be it known that we, ERASTUS E. WINKLEY and FRED V. HART, citizens of the United States, residing at Lynn, in the county of Essex and State of Massachusetts, have invented certain new and useful Improvements in Carbureters for Hydrocarbon-Motors, and we do hereby declare the following to be a full, clear, and exact description of the invention, such as will enable others skilled in the art to which it appertains to make and use the same.

The present invention relates to carbureters for hydrocarbon motors.

One object of the present invention is to provide a carbureter of the above class with a movable deflector for directing onto the vaporizing surface, to a greater or less extent, the air passing through the carbureter,

Another object is to provide a carbureter of the above class with means whereby, when the volume or quantity of air passing through the carbureter is diminished the velocity of such air as it passes over the vaporizing surface shall not be decreased.

With these and other objects in view, apparent to those skilled in the art, the present invention consists in the devices and combinations of devices hereinafter described and claimed.

The rate of evaporation or vaporization of a hydrocarbon or other liquid fuel is dependent upon, among other things, the quantity or volume of air brought into actual contact therewith; and in the present invention we have provided a movable deflector for directing onto the vaporizing surface of the carbureter to a greater or less extent the air which passes therethrough, thus controlling the rate of evaporation and consequently the quality of the mixture. Moreover, the rate of evaporation depends also upon the velocity of the air passing over the surface of the gasoline, and in many devices of the prior art a reduction in the quantity of air passing through the carbureter, following the closing to a greater or less extent of a throttle or in some other manner, necessarily causes a reduction in the velocity of the air passing over the vaporizing surface and consequently an alteration in the quality of the mixture. According to the present invention the throttle or other controlling means is located in such close prox-

imity to the vaporizing surface that, although the air passing through the carbureter may be considerably reduced in quantity, it will not be reduced in velocity as it passes over the vaporizing surface.

In the illustrated embodiment of the present invention, we have shown our improved carbureter as applied to a hydrocarbon motor of the two-cycle type, only a sufficient portion of the motor being shown for a clear understanding of the construction and mode of operation of the carbureter.

In the drawings Figure 1 represents in vertical section our improved carbureter attached to the cylinder wall of a two-cycle hydro-carbon motor. In Fig. 2 the carbureter is shown detached in front elevation, while Figs. 3 and 4 are horizontal sectional views on line 3-3, Fig. 1, and line 4-4, Fig. 2, respectively.

The piston 5 of the motor is mounted to reciprocate within the cylinder 6 and is arranged to uncover the inlet port 7 at or near the end of its downward or expansion stroke to permit a fresh charge to enter the cylinder. As is the common practice with this type of motor the expansion stroke of the piston is utilized to compress within the crank-case the air which is to be supplied to the cylinder with the vaporized gasoline or other fuel, this air passing from the crank-case 8 through the outlet port 9 and air passage 10 to the carbureter and thence through the gas passage 11 to the inlet port 7 of the cylinder. These passages are conveniently formed in a single casting which is secured to the cylinder 6 and crank-case 8 by means of the tap bolts 12.

The carbureter is preferably formed of a casting having a body portion, the upper portion 13 of which is cylindrical as shown in Fig. 4, while the lower portion 14 is substantially U-shape in horizontal section as shown in Fig. 3. A base 15 supporting the body of the carbureter is arranged to be secured to the casting containing the air and gas passages by the bolts 16 and nuts 17, the inlet and outlet ports 18 and 19 of the carbureter registering with the ends of the air and gas passages 10 and 11 respectively.

The preferred form of carbureter shown in the drawing comprises briefly a vaporizing chamber having a vaporizing surface, a gasoline supply and means for regulating

the same, a gasoline valve actuated by the air passing through the carburetor and a combined throttle and deflector for regulating the quantity or volume of air and for 5 directing it to a greater or less extent upon the vaporizing surface.

The vaporizing chamber 20 is located in the lower portion 14 of the carburetor and is formed with a depressed or sunken bottom 10 21 designed to retain any temporary excess of gasoline supplied to the carburetor and prevent its passing down the air passage 10 into the crank case 8 of the motor. At each 15 draft of air through the carburetor some, if not all, of the gasoline in the depressed bottom 21 is vaporized, although evaporation occurs to some extent from other parts of the vaporizing chamber, especially from the side and bottom of the shelf 22. The gasoline 20 is supplied by gravity from some suitable source through a pipe 23 and its flow is regulated by a needle valve 24 actuated by the hand wheel 25. A stuffing box 26 of the ordinary type prevents the leakage of gasoline 25 around the stem of the valve. A short vertical passage 27 is provided through which the gasoline passing to the valve 24 is delivered to the vaporizing chamber 20. At the upper end of this passage is a seat 30 for the valve 28 which normally closes the passage and prevents the escape of gasoline. When, however, this valve is raised in a manner shortly to be described, gasoline flows from the passage 27 onto the shelf 22 35 and over the edge, dripping onto the depressed bottom of the vaporizing chamber. The gaseous mixture passes from the vaporizing chamber 20 through a port 29 to a chamber 30 located in the upper portion 13 of the carburetor and thence through the outlet port 19 and passage 11 into the cylinder of the motor. The port 29 between the two chambers is normally closed by the 40 flange or valve 31 upon the stem 32 of the valve 28 making a sliding fit with said port. The valve 28 in its movements toward and from the valve seat is guided by the four guides 34 for the valve 31, being assisted by the disk 35 on the upper end of the valve 45 stem 32 which slides in a cylindrical guideway 36 in the top of the chamber 30. A screw plug or cap 37 closing the top of the carburetor may be removed when necessary for the purpose of inspection or repair.

The valve 28 operates as follows:—Normally the parts occupy the positions shown in Fig. 1, but the instant the inlet port 7 is uncovered by the piston 5 at or near the end of its expansion stroke, the air compressed 50 in the crank case 8 by such stroke of the piston raises the valve 31 and with it the valve 28. A considerable lift for valve 31 is not required as the gas can pass freely from beneath the valve in all directions save where the guides 34 are located. The raising of

the valve 31 raises at the same time the gasoline valve 28, permitting a certain quantity of gasoline to flow from the passage 27 into the vaporizing chamber to replace that vaporized and withdrawn with the charge then 55 passing through the port 29. When the inlet port 7 is closed as the piston 5 rises in its compression stroke, the pressure on each side of the valve 31 becomes equal and the valve closes by gravity, valve 28 at the same time 75 cutting off the supply of gasoline.

The above specific description has been limited to the old and well-known features in our improved carburetor and we will now 80 describe the new features thereof.

Rotatably mounted in bearings in the carburetor casting near the base 15 is the stud or shaft 38 upon which is fixedly secured by means of a set screw 39 the hub 40. A web 41 rising from the middle of this hub carries the curved face 42 which has a sliding fit between the side walls of the chamber 20. A handle 43 fixed upon the end of the shaft 38 affords convenient means for turning the shaft to adjust the curved face 42 to any 90 desired position. A coiled spring 44 engaging at one end the collar or shoulder 45 upon the shaft 38 and at the other the screw plug 46 acts as a friction device for holding the shaft and curved face in the desired position. 95

The operation of our improved carburetor is as follows:—When the motor is first started, the gasoline valve 24 is regulated by means of the hand-wheel 25 until the proper mixture is obtained. This will be recognized 100 by the fact that any change in the gasoline valve either increasing or decreasing the supply of gasoline is followed by a reduction in the speed of the motor. When the gasoline supply is properly regulated and the motor is operating under normal conditions, the gasoline supplied to the vaporizing chamber is evaporated as fast as it is supplied, and the gradual collection of a considerable quantity of gasoline in the depressed bottom 21 of the vaporizing chamber cannot occur. When it is desired to reduce the speed of the motor, the face 42 is turned down into, say, the position shown in 110 dotted outline, Fig. 1. The reduction in the size of the air passage throttles the air and allows a smaller quantity to pass through the carburetor, although its velocity as it passes over the gasoline on the bottom 21 of the vaporizing chamber is not diminished. 115 Moreover it is directed downward onto the gasoline to a greater degree. The evaporating or vaporizing power of the air will therefore be increased and to such an extent that the air although diminished in quantity will, nevertheless, vaporize the excess of gasoline supplied and flooding of the carburetor and crank-case will be impossible. A reduction in the speed of the motor will 120 at once follow a partial closing of the 125 gasoline valve 28. The gasoline valve 28 will 130

throttle, partially on account of the decrease in the volume of the charge and partially on account of the increase in the richness thereof. If the motor is to run but a short time at 5 the reduced speed, the gasoline valve need not be readjusted, but if for a considerable time we prefer to diminish the supply of gasoline so that a waste of fuel shall be avoided.

10 Although in the illustrated embodiment of our invention we have shown the deflector and throttle as combined in a single device, our invention is not limited thereto as in its broader aspects it contemplates a movable 15 deflector for directing onto the vaporizing surface to a greater or less extent the air passing through the carburetor. It also contemplates broadly a throttle for diminishing the quantity of air passing through the carburetor without reducing its velocity as it 20 passes over the vaporizing surface. Either of these features are valuable and may be used without the other, although we prefer to employ the two in combination as shown 25 in the accompanying drawings.

Having thus described our invention, we claim as new and desire to secure by Letters Patent of the United States.

1. A carburetor, having, in combination, 30 a chamber normally free from excess of unvaporized fuel and provided with an imperforate bottom and with a fuel discharge orifice, means for supplying fuel to the orifice, an air port, and devices normally held 35 in fixed position and adjustable by the operator to deflect the air against the bottom of the chamber to vaporize any excess of unvaporized fuel on the chamber bottom, substantially as described.

40 2. A carburetor, having, in combination, a chamber normally free from excess of unvaporized fuel and provided with a depression to collect and retain any excess of unvaporized fuel and with a fuel discharge 45 orifice located above the depression, means for supplying fuel to the orifice, an air port, and devices normally held in fixed position and adjustable by the operator to deflect the air into the depression to vaporize any excess 50 of unvaporized fuel collected therein, substantially as described.

3. A carburetor, having, in combination, 55 a chamber normally free from excess of unvaporized fuel and provided with a depressed bottom to collect and retain any excess of unvaporized fuel and with a fuel discharge orifice, means for supplying fuel to the orifice, an air port, and devices normally held in fixed position and adjustable 60 by the operator to deflect the air into the depressed bottom to vaporize any excess of unvaporized fuel collected therein, substantially as described.

4. A carburetor, having, in combination, 65 a chamber normally free from excess of un-

vaporized fuel and provided with an imperforate bottom and with a fuel discharge orifice, means for supplying fuel to the orifice, an air port, and devices independent of the fuel supplying means and adjustable by the operator to deflect the air against the bottom of the chamber to vaporize any excess of unvaporized fuel on the chamber bottom, substantially as described.

5. A carburetor, having, in combination, 75 a chamber normally free from excess of unvaporized fuel and provided with a depressed bottom to collect and retain any excess of unvaporized fuel and with a fuel discharge orifice, means for supplying fuel to the orifice, an air port, and devices independent of the fuel supplying means and adjustable by the operator to deflect the air into the depressed bottom to vaporize any excess of unvaporized fuel collected therein, 85 substantially as described.

6. A carburetor, having, in combination, 90 a chamber normally free from excess of unvaporized fuel and provided with a depressed bottom to collect and retain any excess of unvaporized fuel and with a fuel discharge orifice, means for supplying fuel to the orifice, means for supplying air to the chamber, and a deflector located adjacent the depressed bottom and normally held in fixed position to deflect the air into the depressed bottom to vaporize any excess of unvaporized fuel collected therein, 95 substantially as described.

7. A carburetor, having, in combination, 100 a chamber normally free from excess of unvaporized fuel and provided with a depressed bottom to collect and retain any excess of unvaporized fuel and with a fuel discharge orifice, means for supplying fuel to the orifice, means for supplying air to the chamber, and a deflector located adjacent the depressed bottom and independent of the fuel supplying means to deflect the air into the depressed bottom to vaporize any excess of unvaporized fuel collected therein, 105 substantially as described.

8. A carburetor, having, in combination, 110 a chamber provided with a depressed bottom and with a fuel discharge orifice, means for supplying fuel to the orifice, an air passage over the depressed bottom, and means movable from the top of said passage toward the bottom to a position to restrict the area of the passage, substantially as described.

9. A carburetor, having, in combination, 115 an air inlet port, a gas outlet port, a transverse air passage located between the ports and provided with a depressed bottom to retain unvaporized fuel, means for supplying fuel to the carburetor, and movable devices located in the transverse air passage adjacent the depressed bottom and extending 120 downwardly from the top of the passage to-

ward the bottom for restricting the area of the passage, substantially as described.

10. A carbureter, having, in combination, a chamber normally free from excess of unvaporized fuel and provided with a depression to retain any excess of unvaporized fuel and with a fuel discharge orifice located above the depression, means for supplying fuel to the orifice, and means normally held in fixed position and adjustable by the operator to reduce the quantity of air supplied without reducing its velocity over the depression, substantially as described.

11. A carbureter having, in combination, a vaporizing chamber provided with a vaporizing surface, means for supplying fuel thereto, an air actuated fuel valve, and means operating independently of said valve for restricting the vaporizing chamber adjacent the vaporizing surface, substantially as described.

12. A carbureter having, in combination, means including an air actuated fuel valve for supplying fuel thereto, an air port for supplying air thereto, and a throttle for controlling the amount of mixture supplied by the carbureter, said throttle being located between the air port and the air actuated fuel valve, and distant from said valve so that the velocity of the air passing said valve will be progressively reduced the more said throttle is closed, substantially as described.

13. A carbureter having, in combination, a vaporizing surface, means for supplying fuel thereto including a fuel valve actuated by the air passing through the carbureter, and means adjacent the vaporizing surface and normally held in fixed position for reducing the amount and velocity of the air passing the fuel valve without reducing the velocity of said air as it passes the vaporizing surface, substantially as described.

14. A carbureter, having, in combination, a chamber normally free from excess of unvaporized fuel and provided with an imperforate bottom and with a fuel discharge orifice, means for supplying fuel to the orifice, an air passage over the imperforate bottom, and means located in the passage adjacent the bottom normally held in fixed position and adjustable by the operator for closing the upper portion of the passage, substantially as described.

15. A carbureter, having, in combination, a chamber normally free from excess of

unvaporized fuel and provided with a depression to collect and retain any excess of unvaporized fuel and with a fuel discharge orifice located above the depression, means for supplying fuel to the orifice, means for supplying air to the chamber, a pivoted member normally held in fixed position for controlling the air supply, and means for adjusting the position of the member so that the velocity of the air passing over the depression is not substantially reduced when the member is adjusted to reduce the air supply, substantially as described.

16. A carbureter, having, in combination, a vaporizing chamber provided with a depressed bottom, means for supplying fuel to said chamber, an air passage over the depressed bottom, and a pivoted deflector adapted to project downwardly from the top of said air passage with its lower edge adjacent the bottom of the depression, substantially as described.

17. A carbureter, having, in combination, a chamber normally free from excess of unvaporized fuel and provided with a depression to collect and retain any excess of unvaporized fuel and with a fuel discharge orifice, means for supplying fuel to the orifice, a gas outlet port, and means independent of the fuel supplying means for increasing the velocity of the air passing over the depression to vaporize the fuel collected therein when the velocity of the gas passing through the outlet port is reduced, substantially as described.

18. A carbureter, having, in combination, a chamber normally free from excess of unvaporized fuel and provided with a depressed bottom to collect and retain any excess of unvaporized fuel and with a fuel discharge orifice, means for supplying fuel to the orifice, an air port, and means located between the orifice and the port for reducing the amount of air supplied through the port and for deflecting the air into the depressed bottom to vaporize any excess of unvaporized fuel collected therein, substantially as described.

In testimony whereof we affix our signatures, in presence of two witnesses.
